BEAM DYEING-MACHINE.

1,107,095.

Specification of Letters Patent. Patented Aug. 11, 1914.

Application filed September 24, 1912. Serial No. 722,104.

To all whom it may concern:

Be it known that I, FRANK M. MORTON, a citizen of the United States, residing at Phoenix city, in the county of Lee and State of Alabama, have invented certain new and useful Improvements in Beam Dyeing-Machines; and I do declare the following to be a full, clear, and exact description of the invention, such as will enable others skilled 5 in the art to which it appertains to make and use the same.

This invention relates to dyeing, and more especially to stretchers; and its object is to improve the construction and action of a 15 collapsible drum or beam as ordinarily employed for dyeing yarns.

To this end the invention consists first in an improved form of connection between the slat and head of said drum or beam so as 20 to permit the yarn from becoming caught between such parts and broken in winding and unwinding, and also to more thoroughly prevent the passage of the dye from the interior to the exterior of the beam, or the 25 reverse, without it having passed through the yarn; and second to improve the construction of the mechanism for distending the slats—all as hereinafter more fully described and claimed and as shown in the 30 drawings wherein—

Figure 1 is a vertical longitudinal section through the receptacle which contains this beam (the latter being shown therein in side elevation) and through its hollow trunnion. 35 Fig. 2 is a vertical longitudinal section through the beam and the mechanism for distending its slats. Fig. 3 is an enlarged vertical section through said distending mechanism; and Fig. 4 is a cross section on the line 4—4 of Fig. 3. Figs. 5 and 6 are 40 partial cross sections on the lines 5—5 and 6—6 of Fig. 3. Fig. 7 is a perspective detail of a portion of one head of the beam, and parts of the two rings which co-act 45 therewith to produce the recesses in which the extremities of the slats are mounted; and Fig. 7^a is a detail of a portion of the left hand ring shown in Fig. 7, looking at the outer edge thereof. Figs. 8 and 9 are 50 enlarged perspective details of the extremities of the two types of slats employed in this machine.

As is well known to those familiar with this art, the vat or receptacle R in which the 55 yarn on its beam is dyed, may be left open

at its top if the dye liquor is flowed through the receptacle or allowed to stand therein, or would be closed by a cover C securely fastened to the receptacle as at F if the dye liquor is supplied through the inlet I and outlet O under pressure. Said inlet and outlet are typically shown herein for purposes of illustration only, and it is obvious that the course of the liquor through the receptacle could be reversed so that the present inlet becomes the outlet and vice versa. Fig. 1 also illustrates a hollow trunnion T extending from one end of the drum or beam forming the subject matter of this invention, through a bearing B with suitable 60 stuffing box in one end or head of the receptacle R, and the beam is revolved by rotating this trunnion in any suitable way as by means of a gear G and worm W shown in Fig. 1. No claim is made to the parts thus 65 far described.

The beam in the present instance comprises a main shaft 1 having reduced ends forming shoulders 2 and extended thence outward into trunnions 4, and against said 70 shoulders by nuts 3 or otherwise are secured the heads 5 and 7, the latter by preference having a slotted flange 16 which may be secured as by bolts 15 to a similar flange at the inner end of the hollow trunnion T. At the 75 other end of the shaft beyond the head 5, a collar held on the left trunnion 4 by a set screw 8 coacts with the nut 3 to retain a hand wheel forming part of the distending 80 mechanism to be described below. This 90 trunnion may well be supported on a cross bar 9 which in turn is movably and removably supported within the receptacle R by cleats 10 along the sides of the latter; and for centering the trunnion 4 in axial 95 alinement with the center of the hollow trunnion T, I preferably employ a tubular bearing 11 having an enlarged head 12 at its outer end removably fitting in a notched bracket 13 which is carried within the left 100 hand head of the receptacle R as shown in Fig. 1. When this beam is to be removed from said receptacle, it is only necessary to disengage the bolts 15 or other fastening means at the right end of the beam to free 105 it from the hollow trunnion T, after which the left hand trunnion 4 can be pushed farther into the bearing 11 (the cross bar 9 sliding on the cleats 10) until the right hand trunnion is withdrawn from said hol- 110

low trunnion T, and then the entire beam and its bearing 11 can be lifted out of the open top of the receptacle and carried to the warper or other place where the yarn is 5 to be treated. The hand wheel can go with the beam if one such wheel be provided for each beam possessed by the factory, and if not the collar and handwheel can be removed from the left trunnion 4 and placed 10 on the corresponding trunnion of the new beam which replaces the one removed from the receptacle. In any event I would replace the bearing 11 when the new beam is put in.

15 The body of the beam is made up of two series of slats which are alternated with each other and spaced slightly as best seen in Figs. 4, 5 and 6. All these slats have 20 rectangular bodies and are of a length sufficient to reach from one head 5 to the other head 7, and in order to distinguish the slats I will refer to them as movable and fixed respectively. The former is shown in Fig. 8 at 18—the latter in Fig. 9 at 19. Each 25 movable slat has a tenon 17 formed on its end by notching out both corners of the same so that the tenon projects from the end at a point nearly midway between the outer and inner edges of this slat. The fixed slat 30 19 is notched out at 20' at its outer corner only and to a depth longitudinally of the slat somewhat greater than the notches of the movable slat 18, so that the fixed slat has at each extremity what might be called 35 a tongue 20. It is the purpose of the present invention, as one of its principal objects, to provide means for removably connecting the extremities of both kinds of slats with both heads of the beam in such manner that the 40 fixed slats shall have no movement when they are so connected but the movable slats may move radially outward and inward under the influence of an expander yet to be described; and the primary objects sought to 45 be obtained by the peculiar form of connection between said slats and heads is to prevent the yarn from getting over and becoming caught behind the extremities of the slats or any part of the fastening means when the 50 beam is collapsed to reduce the tension on the yarn wound thereon, and furthermore in so far as possible to render the connection between both kinds of slats and the heads fluid-tight in order that the dye liquor may 55 not pass around the ends of the slats and will therefore be forced to pass through the yarn in either direction. The details of this connection are rather intricate in the present embodiment of the invention and will now 60 be described.

As seen in Fig. 7, the inner face of each head is provided with a channel 21 concentric with its axis, and the radially outer wall of the channel is provided with a row 65 of teeth 22. Into this channel are movably

and removably inserted the outer edges of several ring-sections 23—four are employed in the present instance, and of them three are illustrated in edge elevation in Fig. 6. The thickness (which is the radial dimension) of each section is slightly less than the height (which is the radial dimension) of the channel 21, so that the section has some little play therein; and its radially and longitudinally outer corner is notched at intervals to produce teeth 24 corresponding with the teeth 22 within the channel 21. Attention is directed to the fact that the spaces between the teeth of both these sets are wider than the width of the teeth themselves, with the result that the ring-section has some play circumferentially of the head, or in other words longitudinally of the channel 21. Attention is also directed to the fact that the notches 25 producing the teeth 24 do not extend completely through the ring section 23 (as best seen in Fig. 7^a), and therefore said section has a continuous and unbroken web 26 projecting outward into the channel 21. Yet this web is not so thick as the height of said channel below or inside the end of its teeth 22; and it results that the entire section 23 has some considerable play within the channel radially and circumferentially of the beam. The meeting ends of the sections 23 are notched out as best seen at 27 in Fig. 6 so that they will overlap whether the sections are drawn inward toward the axis or pressed outward away from it. Finally, the longitudinally inner edges of the ring sections are provided with notches 28 spaced quite some distance apart and which are to receive the extremities of the movable slats 18 in a manner yet to be described. While the other ring 33 may be 30 made in sections I prefer for sake of simplicity to make it in one piece and secure it to the inner face of the head as by bolts 32 best seen in Figs. 3 and 6. For this purpose its radially inner edge is flat and lies against the flat inner face of the head 5 in Fig. 7, at some distance inside the channel 21 as the boltholes 31 in this ring and the head will indicate. From said flat portion of the ring 33 which extends to the angle 34 (which, when the parts are assembled, will stand just inside the channel 21), the ring turns at right angles longitudinally of the beam and toward the center of the length of the latter into what might be called a foot 35 which will underlie the longitudinally inner edge of the ring sections 23, and the extremity of the foot is then continued radially outward behind said ring sections into what might be called a toe 36; whereby the cross section of the entire ring 33 presents a double angle as indicated in dotted lines in Fig. 3 and best shown in full lines in Fig. 7. The foot of the ring thus forms a bracket underlying the ring sections 23 and assisting 30

the channel 21 in supporting them, while the toe of the ring forms a flange along the edge of the bracket to hold the ring sections 23 thereon. Finally the outer portion of the 5 ring 33 is provided with radial openings of two kinds alternating with each other, and all beginning from a point well within the flat portion of the ring. Those numbered 38 are notches which are carried through the 10 foot and toe and disposed at points opposite the notches 28 in the ring sections 23, and these are to receive the tenons 17 at the extremities of the movable slats 18. The other openings numbered 39 are carried outward 15 through the foot 35 and into the toe 36 but not through the radially outer edge of the latter, and these constitute sockets to receive the tongues 20 at the extremities of the fixed slats 19.

20 It will thus be seen that the ring member 33 has when viewed from one side substantially U-shaped elements which receive and rigidly hold the fixed slats 19 and also serve as spacers and guides for the movable 25 slats 18.

In assembling the parts as thus constructed, the ring sections 23 are inserted in the channels 21 in both heads 5 and 7, and the two ring-shaped brackets 33 brought into 30 place and bolted to said heads as at 32; or, if the ring-sections are short enough, the brackets can be bolted in place first and the ring-sections dropped into position last. In either event their notched-out overlapping 35 ends 27 will engage each other as seen in Fig. 6 and their notches 28 will come opposite the notches 38 in the rings 33. Meanwhile the fixed slats 19 will have been put into place with their tongues 20 engaged in 40 the sockets 39 at which time their extremities 19' will contact with the inner faces of the heads 5 and 7 as the depth of their outer corner notches 20' permit; and these slats are thereby held rigidly or fixedly between 45 the two heads. Meanwhile also, the movable slats 18 will have been put in place in the intervening notches 38 in the ring 33, through which their bodies will extend because their corner notches 17' are not as 50 deep as the corner notches 20' of the fixed slats; and the result will be that the extremities 18' of the movable slats 18 will also rest against the inner faces of the heads 5 and 7 while their wider outer shoulders 17'' 55 will rest in the notches 28 of the ring sections 23 and their narrower inner shoulders 18'' will overlie the flat bodies 33 of the bracket members. Thereby is produced a rigid drum composed of the two heads and 60 the series of fixed slats rigidly although detachably connected therewith, and an expandable and collapsible cage composed of the movable slats alternately interposed between the fixed slats and slidably supported 65 at their extremities by said heads. When

the slats of this cage are moved outward their tenons 17 carry loosely engaging and overlapping the ring-sections 23 with them, even beyond the periphery of the fixed slats and brackets constituting the rigid drum, 70 and this is permitted by the fact that the thickness of the ring sections 23 is less than the height of the channel 21—hence the cage can be expanded to a circumference greater than that of the fixed or rigid drum. When 75 said slats are moved or permitted to move inward, the ring-sections follow them until the latter rest on the brackets and then the tenons 17 leave the inner faces of said sections and move yet farther inward as the 80 depth of the notches 38 permit—hence said cage may be collapsed to a smaller circumference than that of the rigid drum. But in their movements outward or inward their extremities 18' slide in close contact with the inner faces of the heads 5 and 7, and their side faces slide in close contact with the side walls of the notches 38, while the ring sections during their movements inward and outward slide with their outer edges in 85 close contact with the bottom of the channels 21 and their inner edges in close contact with the toes 36 of the bracket—their overlapping ends 27 sliding in close contact with each other as this ring grows or decreases in size. In fact, the sections might be made of flexible material so that they would bend automatically as necessary to preserve the shape of this composite expandible ring whatever its size. The result 90 will be, as proven by experiment, that little or none of the dye liquor will pass around the ends of the slats and between the slats and ring, and hence substantially all of it will be forced through the yarn which is 95 wound on the beam or drum; and absolutely not a strand of this yarn can become entangled between the ring sections and the movable slats or between said sections and the heads of the drum. Therefore 100 one object of my invention is carried out by this construction. It is to be noted that the intermeshing of the parts 22 and 24 and of the ends of the slats with rings, will effectively prevent the yarn from being caught 105 between such parts and broken as it is wound or unwound. I do not wish to be limited to the number, material, or exact shape of these slats, although by preference I would dispose them rather close together; 110 nor do I limit myself to the specific form of rings shown and described. It follows that when the cage is expanded and the yarn is wound thereon, its strands will not touch the fixed slats 19 at all; afterward if it is 115 desired to reduce the pressure of the yarn upon the cage, the movable slats can be collapsed to just such extent that the cage has the same circumference as does the fixed 120 drum; and still later if it be desired to 125

130

move the slats 18 of the cage entirely out of contact with the inner convolutions of the yarn wound thereon, they can be retracted still farther so that the yarn will thereafter be held on the fixed slats alone.

5 The means for effecting the forcible distension of the movable slats and permitting their automatic contraction or collapse will now be described.

10 The expanding or distending mechanism preferably employed in conjunction with the structure above described is perhaps best illustrated in Figs. 2 and 3. Secured within the movable slats 18 at points 15 throughout their length are wedges 40 whose inclined faces are adapted to make contact with the bottom of radial notches 41 formed in spiders or wheels 42 whose hubs 43 are slidably mounted on the main shaft 1, and these wheels are connected in a 20 gang by tie rods 44 as shown. The endmost wheel 45 of the gang or group is formed with integral nuts 46 in its spokes engaged by screws 47 which are rotatably mounted 25 as at 48 through the heads of the beam or drum, and each screw has an enlarged cylindrical head 49 rotating within a stuffing box 50, projecting beyond the head 5 and provided with gear teeth 51. In Figs. 3 and 4 30 I have shown two of said screws, one above and the other below the main shaft 1 and its nuts 3, but it is obvious that more than two could be employed. The hand wheel 52 (above referred to) has an internal gear 35 ring 53 on its inner side, whose teeth engage those numbered 51 on the screw-heads, and it follows that when this hand wheel is turned in the proper direction the screws will be simultaneously rotated and their 40 threads will move the endmost wheel 45 and—through the tie rods 44—the other wheels of the gang so that the entire distending mechanism will be actuated. As seen in Fig. 2, when this distender is moved 45 to the left, the wedges 40 cause the movable slats 18 to expand as above described; whereas, when the gang of wheels is moved to the right, the wedges 40 permit the movable slats 18 to collapse as also above described. I find in use that means for contracting the movable slats need not necessarily be provided, as the natural shrinkage of the yarn and its tension when wound around the fixed slats will be sufficient to 55 cause the movable slats to contract when the support is withdrawn from behind or inside their wedges 40. As above suggested, there may be a handwheel for each beam, but if there be but one handwheel for all 60 the beams in the plant, it will be necessary to remove this handwheel from the left-hand trunnion 4 when a beam is taken from the receptacle R to the warper or elsewhere, immediately placing the handwheel on the corresponding trunnion of the

beam next put into this receptacle, and locking it in place by the collar 6 and set screw 8 or other means which are provided for this purpose. With respect to this feature of my invention, also, I do not wish to be limited to the sizes, materials, or exact details of parts as set forth and as illustrated in the drawings herewith. In fact, some other specific form of distending mechanism might be employed in connection with the 75 specific connection between the various slats and the drum-heads as above described, or conversely the distending mechanism might be used on some other drum. But I find that where power from the handwheel is 80 conveyed from the exterior of the drum or beam to the moving parts within it through two or more screws which rotate in stuffing boxes, through one of its heads, there is extremely little leakage if any at this point; 85 and, as it is one of the principal objects of the present invention to avoid leakage as far as possible, it will be seen that the distending mechanism herein described cooperates nicely with the other feature of this 90 invention.

It will not be necessary for the purpose of this specification to go into the details of the process of winding, dyeing, and unwinding the yarn, further than to say that 95 some mechanism must be provided for rotating the beam within the receptacle R, and for this purpose I have shown the worm gear G and worm W in Fig. 1 simply as 100 illustrative of one of many means which might be employed.

What I claim as new is:

1. In a collapsible beam of the character set forth, the combination with the heads, a series of fixed slats rigidly connecting them, a second series of slats movably mounted between said heads, a shaft, and means for distending the movable slats including an element movable longitudinally upon the shaft; of a plurality of screws rotatably mounted through one of the heads with their shanks engaging threaded openings in said element, and means for turning said screws in unison. 105

2. A beam of the character set forth comprising a drum made up of heads and slats fixedly connecting them, a cage made up of a series of slats interposed between the fixed slats and movably mounted in said heads, and means for distending the movable slats 110 at will. 115

3. A beam of the character set forth comprising a drum made up of heads and slats fixedly connecting them, a cage made up of a series of slats interposed between the fixed slats and movably mounted in said heads, and means for expanding said cage by distending its slats so that the circumference of the cage will be greater than that of the drum, or for contracting said cage by col- 125 130

lapsing its slats so that the circumference of the cage will be smaller than that of the drum.

4. A beam of the character described comprising two heads whereof each has an internal annular channel with teeth projecting radially inward from its outer wall, a ring made in sections having lapping meeting ends, and their outer edges toothed to engage the teeth within said channel and their inner edges notched at intervals, a ring-shaped bracket secured to the inner face of the head and having notches opposite those in said ring-sections, and slats extending from one head to the other and having their extremities movably mounted in said notches.
5. A beam of the character described comprising two heads whereof each has an internal annular channel with teeth projecting radially inward from its outer wall, a ring made in sections having lapping meeting ends and their outer edges toothed to engage the teeth within said channel and their inner edges notched at intervals, a ring secured to the inner face of said head and having its body bent inward into a foot underlying said ring sections and thence radially outward into a toe extending across the inner edge of said sections, said foot and toe having notches registering with those in said sections, and slats whose extremities are movably mounted in said notches.

6. A beam of the character described comprising two heads whereof each has an internal annular channel with teeth projecting radially inward from its outer wall, a ring made in sections having lapping meeting ends and their outer edges toothed to engage the teeth within said channel and their inner edges notched at intervals, a ring secured to the inner face of said head and having its body bent inward into a foot underlying said ring sections and thence radially outward into a toe extending across the inner edge of said sections, said foot and toe having notches registering with those in said sections and interposed sockets, a series of movable slats whose extremities pass through said notches in the ring and loosely engage those in the sections, and a series of fixed slats having tongues at their extremities rigidly engaging said sockets.

7. A beam of the character described comprising two heads whereof each has an internal annular channel with teeth projecting radially inward from its outer wall, a ring made in sections having lapping meeting ends and their outer edges toothed to engage the teeth within said channel and their inner edges notched at intervals, a ring secured to the inner face of said head and having its body bent inward into a foot underlying said ring sections and thence radially outward into a toe extending across the inner edge of said sections, said foot and toe

having notches registering with those in said sections and also having interposed sockets, a series of movable slats having tenons at their extremities, their bodies passing through the notches in said ring and their tenons standing radially inside said ring sections, and a series of fixed slats having tongues at their extremities fixedly mounted in said sockets.

8. A beam of the character described comprising two heads whereof each has an internal annular channel, a ring made in sections having their outer edges within said channel and their inner edges notched at intervals, a ring secured to the inner face of said head and having its body bent inward into a foot underlying said ring sections and thence radially outward into a toe extending across the inner edge of said sections, said foot and toe having notches registering with those in said sections and interposed sockets, a series of movable slats whose extremities pass through said notches in the ring and loosely engage those in the sections, and a series of fixed slats having their extremities rigidly engaging said sockets.

9. A beam of the character described comprising two heads whereof each has an internal annular channel, a ring made in sections having lapping meeting ends, the sections standing within said channel and having their inner edges notched at intervals, a ring shaped bracket secured to the inner face of said head and having notches registering with those in said sections and also having interposed sockets, a series of movable slats having tenons at their extremities, their bodies passing through the notches in said bracket and their tenons standing radially inside said ring sections, and a series of fixed slats having tongues at their extremities fixedly mounted in said sockets.

10. A beam of the character set forth, comprising a drum made up of heads and fixed slats between them, a cage made up of a series of radially movable slats disposed between said fixed slats, means for distending the movable slats, and intermeshing connections between the ends of the movable slats and said heads.

11. A beam of the character set forth, comprising a drum made up of heads and fixed slats between them, a cage made up of a series of radially movable slats disposed between said fixed slats, means for distending the movable slats, expansible rings at the ends of the movable slats, and intermeshing connections between the heads and said expansible rings.

12. A beam of the character set forth, comprising a drum made up of heads and fixed slats between them, a cage made up of a series of radially movable slats disposed between said fixed slats, means for distending the movable slats, expansible rings at the

ends of the movable slats and intermeshing connections between the movable slats and said expandible rings.

13. A beam of the character set forth comprising heads, radially movable slats, means for actuating said slats, expanding rings at the ends of the slats and intermeshing connections between said rings and the heads.

10 14. A beam of the character set forth comprising heads, radially movable slats, means for actuating said slats, expanding rings at the ends of said slats and intermeshing connections between said rings and slats.

15 15. A beam of the character set forth comprising heads, radially movable slats, means for actuating said slats, expanding rings at the ends of said slats, intermeshing connections between said rings and slats and 20 intermeshing connections between said rings and heads.

16. A beam of the character set forth comprising two heads whereof each has an internal annular channel formed in one wall 25 with teeth, an expansible ring to enter each channel and having teeth to intermesh with the teeth in the latter, radially movable slats inclosed by said rings and means for moving the slats.

30 17. A beam of the character described comprising heads, radially movable slats between the same, expansible rings adjacent the heads and having their inner edges notched at intervals, U-shaped elements carried by the heads, fixed slats arranged between said heads and engaged with said ele-

ments, movable slats arranged between said elements and engaged with the notches in said expansible rings, and means for actuating the movabale slats.

18. A beam of the character described comprising two heads whereof each has an internal annular channel, a ring made in sections having their outer edges engaging said channel and their inner edges notched at 45 intervals, a ring-shaped bracket secured to the inner face of the head and having notches opposite those in said ring sections, and slats extending from one head to the other and having their extremities movably 50 mounted in said notches.

19. A beam of the character described comprising two heads whereof each has an internal annular channel, a ring made in sections having their outer edges engaging said 55 channel and their inner edges notched at intervals, a ring-shaped bracket secured to the inner face of said head and having its body bent inward into a foot underlying said ring sections and thence radially outward 60 into a toe extending across the inner edge of said sections, said foot and toe having notches registering with those in said sections, and slats whose extremities are movably mounted in said notches.

In testimony whereof I have hereunto set my hand in presence of two subscribing witnesses.

FRANK M. MORTON.
